By *Clarence O'Brien*,
Attorney

UNITED STATES PATENT OFFICE

FRANCIS X. SMITH, OF NEW YORK, N. Y., ASSIGNOR OF ONE-HALF TO GEORGE W. BEATTY, OF BROOKLYN, NEW YORK

EMERGENCY RELEASE VALVE

Application filed November 8, 1930. Serial No. 494,373.

This invention relates to improvements in emergency release valves and is an improvement over that type of valve shown in application Serial No. 488,441, filed October 13, 1930 by George W. Beatty in which I am assignee of part interest.

This invention resides in an automatic valve device for releasing the liquid content of a vessel or container when subjected to a predetermined temperature to prevent the liquid content from being affected by a temperature which might be injurious to the liquid or to the vessel in which it is contained. For instance, the device might be installed upon a water tank, automobile radiator or the like, and set to operate should the temperature approach the freezing point, to avoid solidifying of the content and the possible breaking of the vessel due to expansion. These features are clearly set forth in the above mentioned application, but this device differs therefrom in details of construction and certain refinements which not only reduces the cost of manufacture and improves the appearance of the device, but also renders the device more positive of operation, and facilitates the quick reassembling of the parts after each operation.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a side elevational view of my release valve attached to a container or vessel, a portion of the same being shown in section.

Figure 2 is an enlarged vertical longitudinal sectional view on the line 2—2 of Figure 1.

Figure 3 is a view similar to Figure 2 but showing the valve in open or released position.

Figure 4 is a bottom plan view.

Figure 5 is a collective perspective view of the several parts which constitute my invention.

Referring to the drawing by reference

characters, the numeral 10 designates my improved emergency release valve in its entirety which includes a head 11 having a bore 12 therethrough and a threaded nipple 13 extending from one side of the head, while extending from the opposite side is a reduced annular portion 14 within which is an enlarged recess 15 which communicates with the bore 12. The sides of the head 11 are provided with flat nut surfaces with which a wrench may engage for screwing the nipple 13 to the vessel on which the valve is to be installed.

Fixedly secured in the side walls of the reduced portion 14 and diametrically opposed, are pins 16, the inner ends of which extend into the recess 15 while the outer ends extend beyond the sides of the reduced portion 14. The inner side walls of the recess 15 are provided with an annular beveled seat 17 with which a valve member 18 coacts. The valve member 18 is in the form of a disc provided with a beveled side wall 19 and with a cavity 20 in its under side, while extending from the opposite side of the disc or valve member is a stud 21, the same being provided with a spiral groove 22 for a purpose to be presently explained. The stud 21 rises centrally of the valve member and threadedly connected to the stud 21 is the pointed end of an inverted conical spring 23. Certain of the convolutions of the spring 23 are received in the spiral groove 22 on the stud 21, while the enlarged or base end of the spring seats against the top of the recess 15. Certain of the convolutions at the base end of the spring are engaged by the pins 16, and which serve to hold the spring connected to the head, while the spring in turn supports or is connected to the valve member 18.

Telescoping the reduced portion 14 of the head is the open end of a cylindrical casing 23, the bottom of which supports a cup shaped member 24, which is rigidly secured within the casing and extending through the bottom of the casing and the cap 24 is a drain outlet 25. The casing 23 is provided with diametrically opposed bayonet slots 26 which open through the peripheral edge of the open end of the casing, and which slots receive the

outer ends of the pins 16 in order to lock the casing in position upon the head. Connection is effected by causing the pins to enter through the bayonet slots after which the casing is pushed upwardly and given a slight turn in order to dispose the pins against the closed ends of the said bayonet slots.

The cup shaped member 24 is provided with an annular groove 27 which receives the 10 lowermost convolution of a helical spring 28. This spring 28 is slightly wider at its base than at its top, the top convolution being engageable with a breakable liquid containing element 29 which in the present instance 15 is shown as a hollow globular glass bulb containing a liquid 30. Although a glass breakable bulb has been shown and mentioned, it will be understood that various other types of fuses may be used in connection with the 20 device such as a fusible metal ball which will melt under a predetermined temperature. Such a metal ball would of course be used where heat temperatures are intended to actuate the valve.

25 The top of the breakable element 29 seats in the cavity 20 of the valve member 18, and by reason of the fact that the tension of the spring 28 is greater than the tension of the spring 23, the valve member 18 will be held 30 seated upon the seat 17 due to the pressure exerted by the spring 28 against the breakable element 29 which in turn is engaging the valve member. In order that the breakable element 29 may be seen without removing 35 the casing 23, I provide window openings 31 in the side walls of the casing, and if desired, the said openings may be closed by isinglass or the like, to cause the entire liquid released by the valve when opening to pass 40 through the discharge outlet 25. As shown, the discharged liquid will pass out of the window openings 31 in addition to the discharge outlet 25.

In practice, a device such as I have shown 45 and described may be installed upon any tank or vessel containing a liquid which is adapted to be released when the temperature reaches a predetermined degree. For instance it may be desired to protect the contents of a vessel or radiator from freezing 50 whereupon the emergency release valve 10 may be screwed into the bottom B of the vessel. The contents 30 of the bulb 29 is such that the bulb will break by reason of a temperature 55 higher than the temperature for the freezing of the liquid contents of the vessel. Assuming that the valve member 18 is in closed position as shown in Figure 2 and the breakable element 29 should become shattered, the tension of the spring 28 will become spent, whereupon the tension of the 60 spring 23 will move the valve member 18 to the open position shown in Figure 3. When in this position, the liquid content of the vessel is free to flow through the casing in the

direction of the arrows shown in Figure 3 and out through the discharge opening 25. In addition to the above function of the spring 23, the same will loosen any accumulation which might interfere with the free flow of liquid released from the vessel.

After one operation of the release valve, it becomes necessary to reset the same, whereupon the casing 23 may be quickly separated from the head by merely imparting a slight turn thereto and pulling downward upon the casing so as to separate the pins 16 from the bayonet slots. The operator proceeds to place a new breakable element 29 upon the top of the spring 28 which automatically 80 centers the element 29 with respect to the valve member 18 so that when the casing is again connected to the head 11, the breakable element 29 accurately seats with the cavity 20 and effects a more perfect seating of the valve member 18 upon its seat 17. By these various improvements in construction, it will be understood that the release valve 85 will operate more efficiently and more positively as the arrangement of the springs and their relation to other parts is such that there is no possibility of the valve member sticking and not opening when released. Furthermore, the construction of this device over the device mentioned in the pending application renders the valve simple and inexpensive in manufacture and easy in assembly and in the resetting of the valve.

Having thus described the invention, what I claim as new and desire to secure by Letters Patent is:—

1. An emergency release valve comprising a head having a bore which opens into an enlarged recess therein, a valve seat provided on the walls of said recess, a valve member for engagement with said seat, an inverted conical spring having one of its ends secured in said recess and its other end connected to said valve member centrally thereof, a thermal responsive breakable liquid containing element seated against said valve member, a casing having a drain outlet, means for detachably securing said casing to said head, said means including locking pins which extend into said recess and which engage certain of the convolutions of said inverted conical spring to secure the same within said recess, and a spring interposed between said breakable liquid containing element and one end of said casing to maintain the breakable element in seated position.

2. An emergency release valve comprising a head having a bore opening into an enlarged recess provided therein, a valve seat provided on the walls of said recess, a valve member for engagement with said seat and having a cavity in one side thereof, a stud extending centrally from said valve member, from the opposite side thereof, said stud having a spiral groove externally therein, a

conical spring having its base end seated against a wall of said recess and the convolutions of the pointed end threaded to said spiral groove in said stud, a thermal responsive breakable element seated in said cavity, a hollow casing having a drain opening therein, means for detachably connecting said hollow casing to said head, and a spring having one end seated against said breakable element and its opposite end anchored to one end wall of said casing, said last mentioned spring being of a greater tension than the tension of said conical spring.

In testimony whereof I affix my signature.

FRANCIS X. SMITH.
